COMBINED DISPLAY AND SHIPPING
PACKAGE

Herman C. Bohnke, Carnegie, Pa., assignor to
Superior Paper Products Company, Carnegie,
Pa., a corporation of Delaware

Application June 17, 1932, Serial No. 617,772

2 Claims. (Cl. 206—45)

This invention relates to a combination shipping package and display case and has for its primary object, generally stated, the provision of a combination of this character made of corrugated paper, or like material, which is adapted for use more especially for shipping and storing, as well as displaying, flower and garden seeds or other commodities contained in packages of the type in which such seeds are customarily sold.

10 A more particular object is to provide a combination display case and shipping container of the aforementioned character which is made of light weight inexpensive material and comprises comparatively few parts all of which may be prepared by the manufacturer and shipped to the user in the flat and in such a condition that they may be easily and quickly assembled by any unskilled laborer.

These and other objects, as well as the various other novel features and advantages of the invention, will be apparent when the following detailed description is read in conjunction with the accompanying drawings, wherein, Fig. 1 is a perspective view of a partly assembled display case and shipping container therefor constructed in accordance with the invention; Fig. 2 a front elevation of the display case; Fig. 3 a sectional view taken on the line III—III of Fig. 2; Fig. 4 a plan view of the display-case supporting back-rest or prop before it is folded; Fig. 5 a perspective view of the container comprising the housing of the display case with the compartment-forming fillers removed; Fig. 6 is a sectional view taken on the line VI—VI of Fig. 5; Fig. 7 a plan view of one of the transverse pocket-forming filler sections before it is folded; Fig. 8 a perspective view of the filler shown in Fig. 7 after it is folded; and Fig. 9 an elevational view of one of the vertically disposed partition strips or pocket-forming fillers.

40 Referring to the drawings, the numeral 1 designates an open-faced box-shaped container formed of corrugated paper board or the like which constitutes the housing of a display case such as is contemplated by this invention and which is made from a single precut sheet of paper board provided with a pair of creased flaps 2 and 3 at its upper and lower ends, for a purpose which will presently appear, and folded to shape. In such container there is provided a plurality of systematically arranged vertically and transversely disposed detachable fillers 4 and 5 which form therein a plurality of pocket-like compartments 6 for the reception of various articles such as packages of flower and garden seeds, or other packages of that character. The number and

size of these fillers, as well as the size of the container itself, depend of course upon the size and number of compartments desired.

The vertically-disposed fillers 4 as shown in Figs. 1, 2, 3 and 9 comprise simply a plurality of plain strips of paper board having a length equal to the length and a width slightly less than the depth of the container 1. The side walls of the compartments 6 are formed by these strips, they being arranged in uniformly spaced parallel relation across the container and provided on their exposed edges with a series of equally spaced inclined slots 7 within which the transverse fillers 5 are engaged. These latter fillers 5 are also made of plain sheets of paper board the length 70 of which is equal to the width of the container-forming housing and the width to the dimension required for the depth and width of compartments 6 desired, this, of course, being limited by the depth of the housing and the spacing of the slots 7 in the vertically-disposed fillers 4. Creases 8 and 9 are made in these fillers parallel to the sides thereof to facilitate their being folded into the form of an unequal-sided flat-bottomed trough, the width and length of the respective 75 side walls of which are determined by the spacing and inclination of the slots 7 in the vertical fillers 4. The depth and slant of these slots in turn are determined by the size of the compartments required and the angle at which it is desired to support the case, the angle of their slant being such that it places the walls of the compartments in vertical planes when the case is on display. To permit the transverse fillers 80 being mounted in the slots 7 of the vertical fillers, they are provided with a series of slots 11 cut through that portion thereof which forms the bottom of the trough and the part of the back wall which rests below the bottoms of the slots 7 in 85 which the back wall of the filler rests. Through 90 these slots 11 the portions 12 of the vertical fillers 4 disposed between the slots 7 in the latter fillers project to form the side walls of the compartments 6.

As appears most clearly in Fig. 4, the slots 7 100 cut in the vertical filler sections 4 are made with a width which is sufficient to accommodate two thicknesses of the paper board used in making the transverse fillers 5 and in them the back and front wall portions of the adjacent transverse fillers 5 are positioned, except in the upper and lower slots where only one wall of the transverse fillers is positioned. These latter slots, however, have the same width as the others, and in them the flaps 2 and 3 which are provided on the upper 110

and lower walls of container 1 are fitted when the filler assembly is placed in the container, the function of these flaps being to hold the fillers in place when the case is assembled.

- 5 For supporting the display case in an inclined upright position on the floor or on a display counter a detachable back-rest or prop 14 is provided, which may be removed and placed in the front of the container 1 when the latter is packaged for storage or shipment. As shown in Fig. 4, this prop comprises a strip of paper board in which a crease 15 is provided nearer one end than the other, to adapt it to be folded into the shape of a letter V, and bifurcated projections or lugs 16 and 17 on its ends which fit in slots 18 and 19 cut in the back of casing 1. The slots 22 and 23 in these lugs 16 and 17 when in position straddle the vertical filler 4 disposed in the center of the container and aid in holding the prop in place.
- 10 For shipping and storing the above-described display case, a paper board carton 20, which is adapted to just receive the container 1, is provided. This carton, like the container 1, may be made in any suitable fashion, but preferably out 15 of a single sheet of paper board which is cut and creased in a well known fashion adapting it to be readily folded and assembled. In assembling the combined parts, the prop 14 is placed in the front of the container 1 on the top of the fillers 20 4 and 5 and the container 1 then slid into the carton 20 and the ends of the latter closed.
- 25 For shipping and storing the above-described display case, a paper board carton 20, which is adapted to just receive the container 1, is provided. This carton, like the container 1, may be made in any suitable fashion, but preferably out 20 of a single sheet of paper board which is cut and creased in a well known fashion adapting it to be readily folded and assembled. In assembling the combined parts, the prop 14 is placed in the front of the container 1 on the top of the fillers 25 4 and 5 and the container 1 then slid into the carton 20 and the ends of the latter closed.
- 30 As will be appreciated by those skilled in the art, the parts of this construction may be all cut and creased by the manufacturer and shipped to 35 the user in the flat as the user can easily and readily assemble them whenever he desires. As is also obvious, the display case may be filled before shipment, as well as replaced for storage purposes in the outer container if desired. In 40 addition, it has the added advantages that it is sturdy of structure, light of weight, and comparatively inexpensive.

According to the provisions of the patent stat-

utes, I have explained the principle and mode of operation of my invention, and have illustrated and described what I now consider to represent its best embodiment. However, I desire to have it understood that, within the scope of the appended claims, the invention may be practiced otherwise than as specifically illustrated and described.

I claim:

1. A display case formed of paper board comprising an open-faced container provided with creased flaps on two of its edges, a series of partition-forming strips mounted in said container in uniformly spaced relation and held therein by said flaps which are engaged in slots provided in said strips, and a series of trough-like fillers mounted one below the other in a series of aligned inclined slots provided in said partition-forming strips, the trough-like fillers having slots in them through which said strips project to form therewith a plurality of pocket-like compartments disposed at an angle to the face of said container. 85

2. A display case formed of paper board comprising an open-faced container, a series of vertical partition-forming strips mounted in said container in uniformly spaced parallel relation, a series of trough-like fillers mounted one below the other in a series of inclined slots provided in said partition-forming strips, the trough-like fillers having slots in them through which said strips project to form therewith a plurality of pocket-like compartments disposed at an angle to the face of said container, and a folded prop member detachably engaged in the back of said container for supporting said case in an inclined upright position, said container having spaced openings in its rear wall opposite one of said vertically strips and said prop being provided with slots in its ends, and its ends inserted in said openings with said slots straddling the vertical strip arranged in the container opposite the prop receiving openings. 100
